(57) **CLAIM**

The ornamental design for a swaddle with zipper, as shown and described.

DESCRIPTION

FIG. 1 is a perspective view of the swaddle with zipper, showing the new design;

FIG. 2 is a front elevational view of the swaddle with zipper thereof;

FIG. 3 is a rear elevational view of the swaddle with zipper thereof;

FIG. 4 is a left side elevational view of the swaddle with zipper thereof;

FIG. 5 is a right side elevational view of the swaddle with zipper thereof;

FIG. 6 is a top plan view of the swaddle with zipper thereof; and

FIG. 7 is a bottom plan view of the swaddle with zipper thereof; and,

FIG. 8 is an alternate perspective view of the swaddle with zipper thereof in an open configuration.

The broken lines shown illustrate portions of the swaddle with zipper that form no part of the claimed design.

1 Claim, 5 Drawing Sheets
